E. F. CODY

GOLF BALL TEE

Filed May 28, 1927

FIG. 1.

FIG. 2.

INVENTOR.

EARL F. CODY.

BY.

K. A. Duckman
ATTORNEY.

UNITED STATES PATENT OFFICE.

EARL F. CODY, OF LONG BEACH, CALIFORNIA.

GOLF-BALL TEE.

Application filed May 28, 1927. Serial No. 194,875.

An object of my invention is to provide means for securing two wooden golf tees together. It has been found that wood is more suitable for a golf tee in that metal, when it is lost on the course, tends to clog or dull the lawn-mower, whereas, wood is more readily cut and does not affect the mower. It is very desirable that the tee be anchored in order that it will not be lost when hit by the player, and since wood will break it is not practical to provide a permanent tie.

A further object of my invention is to provide a detachable coupling means between two wooden tees.

A still further object is to provide a tee coupling which is simple in construction, inexpensive to manufacture, and which may be readily and quickly attached to the tees. Other objects, advantages, and features of invention may appear from the accompanying drawing, the subjoined detailed description, and the appended claims.

In the drawing:

Fig. 1 is a side elevation of a pair of tees secured together by my fastening means.

Fig. 2 is a plan view of one of the washers.

Referring more particularly to the drawing:

A pair of wooden tees 1, 2 which tees may be of usual and well-known construction, but I prefer that the heads 3 thereof shall have straight sides and that there shall be an abrupt taper, as at 4, extending from the head to the shank 5. A washer 6 fits over each of the shanks 5 and is provided with an inwardly projecting tip 7 which extends into the wooden shank to hold the washer securely in position. Also, due to the abrupt cut under the head 3 the washer will fit closely under the head thus protecting it against being struck by the club. If the

washer should be repeatedly struck by the club it will wear the shank and cause the same to break.

The two washers 6, 6 after being placed on a pair of tees are connected together by a string, or the like, 8, which string may fit into a notch 9 formed in the washer 6. It will be observed that my washers can be readily removed or placed on a tee and if a tee becomes damaged in any way, it may be removed and thrown away and a new one placed in the washer. Thus I provide an inexpensive and effective anchoring means for the tees, and since both tees in the pair are alike, it is not necessary to select the proper tee upon which to place the ball.

Having described my invention, I claim:

1. In combination with a pair of wooden tees a detachable metal washer adapted to slip over the shank of each tee and means extending inwardly from said metal washer adapted to frictionally engage the shank of the tee and a string connecting said metal washer.

2. In combination with a pair of wooden tees, a metal washer adapted to slip over the shank of each tee, and a string connecting said metal washers, said metal washers being formed with an inwardly projecting tip adapted to extend into the shank of the tee.

3. In combination with a pair of wooden tees, a metal washer adapted to slip over the shank of each tee, and a string connecting said metal washers, said metal washers being formed with an inwardly projecting tip adapted to extend into the shank of the tee, and a recess formed in each of the washers in which the connecting string is adapted to fit.

In testimony whereof, I affix my signature.
EARL F. CODY.
